UNITED STATES PATENT OFFICE.

CORNELIUS COLLINS, OF ALBIA, IOWA, ASSIGNOR OF ONE-HALF TO GEORGE W. McBURNEY, OF SAME PLACE

GARDEN PLOW, CULTIVATOR, &c.

SPECIFICATION forming part of Letters Patent No. 412,840, dated October 15, 1889.

Application filed March 8, 1889. Serial No. 302,448. (No model.)

To all whom it may concern:

Be it known that I, CORNELIUS COLLINS, a citizen of the United States, residing at Albia, in the county of Monroe and State of Iowa, have invented a new and useful Improvement in Garden Plows, Cultivators, Harrows, &c., of which the following is a specification.

My invention relates to an improvement in garden plows, cultivators, harrows, &c.; and it consists in the peculiar construction and combination of parts hereinafter more fully described, and particularly pointed out in the claims.

In the drawings, Figure 1 is a perspective view of my invention, showing the same arranged for use as a garden-plow. Fig. 2 is a similar view of the same arranged for use as a cultivator. Fig. 3 is a similar view showing the same arranged for use as a harrow.

20 A pair of curved bars A, which are arranged parallel with each other, have their rear ends connected by a curved push-yoke B, which is adapted to fit against the body of the operator and enable him to propel the machine. Between the front ends of the curved bars A is secured a shaft C, on which is loosely mounted a driving and supporting-wheel D, and attached to the latter and concentric with its hub is a gear-wheel E. A casting F connects the bars A at a slight distance in rear of the wheel D, and is provided with a vertical central opening G. The wings or plates H, formed at the ends of the casting, bear against the inner sides of the bars A and are bolted thereto, as shown. A cross-bar I also connects the bars A, and is arranged at a suitable distance in rear of the casting F.

40 The mechanism hereinbefore described constitutes the main frame and driving-wheel of the machine, which remains unchanged under all conditions in which the machine is designed to operate.

I will now describe the plow attachment illustrated in Fig. 1. a is a substantially S-shaped standard, which has its upper end reduced in size to form a bolt or pivotal arm b, which extends through the opening G, and to the upper end of which is screwed a nut c, whereby the said standard is pivotally connected to the casting F. To the lower end of

the standard is secured a plowshare d, of the usual or any suitable form, and bolted to the lower end of said standard and projecting upward therefrom is a single plow-handle e, the upper end of which is adapted to extend between the rear portions of the bars A and to be grasped by one hand of the operator, whereby he is enabled to direct the plow at any desired depth and to swing the same laterally to avoid obstructions or plants.

I will now describe my improved cultivator attachment. A bolt f is swiveled in the opening G of casting F, and has an eye at its lower end, through which is extended a longitudinally-movable rod g, the front end of the same being curved downward to form a hook i.

k represents the cultivator-beam, to the front end of which, under its lower side, is bolted a plate l, provided at its front end with a pair of ears m. A link-arm n has an eye at its upper end, through which the rod g passes, and the lower end of the said link-arm is pivoted between the ears m on a bolt o. At the rear end of the beam k is an eye-bolt p, to which the rear end of the rod g is connected, as shown.

From the foregoing description it will be obvious that the cultivator-beam is loosely connected to the main frame of the machine, that it is adapted to be moved longitudinally for some distance independently thereof, and that the front end of the cultivator-beam may be raised or lowered independently of the rear end thereof, to the end that the cultivating-shovels attached to the standards may be caused to operate in the soil at any desired inclination. The rearmost standard s has an integral rearwardly-inclined extension-arm t formed at its upper end, through which passes a cross bar or rung u. A pair of handles v, which are similar to plow-handles, have their lower front ends secured on opposite sides of the cultivator-beam by means of bolts w, and are provided near their rear ends with openings which receive the ends of the cross-bar u. Both hands of the operator grasp the handles v, and the operator is thereby enabled to manipulate the cultivator with the utmost facility.

I will now describe my improved harrow

attachment, which comprises a V-shaped harrow-frame a' , having the harrow-teeth b' , and provided with the handle c' and the braces d' . The handle has its front end secured to the front of the harrow-frame, and the braces have their upper ends bolted to the handle and their lower ends bolted to the cross-beam at the rear of the harrow-frame. A draft-iron e' is bolted on the front side of the handle, near the lower end thereof, and has an eye formed in its upper end, to which is linked a hook f' , the latter being adapted to engage the eye of the swiveled bolt, and thereby connect the harrow attachment to the main frame. The operator manipulates the harrow attachment by grasping the handle c' , as is obvious.

Having thus described my invention, I claim—

- 20 1. The frame A, having the swiveled bolt f , in combination with the rod g , passed through an eye at the lower end of the bolt and having the hook or stop at its front end, the beam carrying the implement to act on the soil and having its rear end loosely connected to the rear end of said rod, and the link-arm having its upper end loosely connected to and adapted to slide longitudinally on the rod and its lower end pivotally connected to the lower end of the frame, substantially as described.
- 25 2. The frame comprising the parallel compound curved bars A , the yoke B , connecting

the rear ends of the said bars, the shaft connecting the front ends of the bars, and the driving and supporting wheel mounted on said shaft, substantially as described.

3. The frame having the swiveled bolt f , the rod g , connected at its front end to said bolt and arranged at right angles thereto, and the beam carrying the implement to act on the soil, said beam being pivotally and loosely connected to the rod g , so as to slide thereon, as set forth.

4. The frame having the wheel D and bars A, combined with the beam carrying the implement to act on the soil, the swiveled bolt f on the frame-bars A, the beam of the implement being connected to the bolt f , as set forth.

5. The frame comprising the parallel bars A, shaped and curved substantially as shown, and having the curved yoke B connecting their rear ends, the wheel D, journaled between their front ends, and the casting F, connecting the bars A in rear of the wheel and providing a bearing for a pivot-bolt, to which the implements are connected, as set forth.

In testimony that I claim the foregoing as my own I have hereto affixed my signature in presence of two witnesses.

CORNELIUS COLLINS.
